J. P. FAIRLAMB & M. DUNOTT.
CRACKER MACHINE.

Patented June 13, 1831.

DANAS P. FAIRBANK & MILLER DUNNETT.

6574

Letters Patent.

The Schedule referred to in these Letters Patent, and making part of the same, containing a description in the words of the said DANAS P. FAIRBANK & MILLER DUNNETT, themselves of their improvement for modelling and casting bronzes, &c. tin cans, tanks, and making maners.

We provide a cylinder, similar in form to the common pulley used for belts, in the periphery or rim of which, we insert, or attach the moulds, and another cylinder, with plain periphery (which periphery may be sheet lead or other proper substance) both moveable, or revolving on their centres, and so placed that the peripheries of the plain cylinder come in contact with the face, or outer edge of the moulds, alternately, as the cylinders revolve upon their centres, nearly at a right angle, with a line parallel with the centres of the cylinders, and the bottom and top points of their peripheries, exciting nearly a horizontal pressure, (this place of pressure may, however, be varied to suit different arrangements, a stationary spring or scraper, may be fixed alternately to come in contact with the outside of the moulds, and admitting their faces to pass clear of any obstruction thereby, from following, that slide in the moulds, like common followers in cylinders.) Stands, or steeds, intend the proper distance through the rim of the cylinder, when the mould is full, on the inside of this rim, is another cylinder, revolving when necessary, the diameter being half diameter of the cylinder in which it revolves, and to stationary centre, the periphery of which, comes in contact with the ends of said steeds, or stands, and thereby moves the following to the face of the moulds, and encloses the same.

cracked, or cracked of the moulds, alternately to fall, perpendicular, upon a conductor, revolving around two rollers, similar to those in common use - the dough must, in the first place be prepared as usual, then cut in slices, or made in rolls of the proper size and consistency, it is then passed between fixed rollers or cylinders, by which it is rolled to an equal & proper thickness, to be received into the moulds, and conducted by a constant motion, to the place of pressure into the moulds; where received (or the necessary quantity) into the moulds, it remains there until discharged, or expelled therefrom as aforesaid, in proper forms as moulded, and is received as aforesaid upon the said conductor, or instead of inserting the moulds in the aforesaid rim of a cylinder, we insert them in links of a pitch chain, revolving as common pitch chains around two cylinders, or pitch wheels, and to be operated on as aforesaid, by constructing the one of those wheels, directly above the pressing cylinders, or nearly so, so as to admit the free passage of the said studs or shanks of the followers, the other pitch wheel, operating on the said studs, or shanks which pass through the pitch chain, in the same manner as those passing through the rim of the aforesaid cylinder are operated on, by the aforesaid small cylinder - The motion may be given to the cylinders, by any of the well known powers, now in use, and must be equal surface with the face, or entire edge of the moulds, being considered the surface of the cylinder, to which they are attached, or pass around. We therefore claim the exclusive right and benefit of moulding and baking crackers, biscuits, cakes, and making wafers, by cylindrical pressure, and such other parts of the aforesaid machinery, as are not herein or in use. In witness whereof we have hereunto set our hands, this 21st day of April in the year of our Lord, one thousand eight hundred and thirty one.

Witness, James Jordan
